(57) **CLAIM**

The ornamental design for a textile article including a perforation pattern, as shown and described.

DESCRIPTION

The sole FIGURE is top plan view of a textile article including a perforation pattern showing my new design. The bottom plan view of the textile article of the sole FIGURE is the same as the illustrated top plan view. Accordingly, the bottom plan is not illustrated. The dash-dot lines in the FIGURE, defining the bounds of the claimed design, form no part thereof.
